(57) **CLAIM**

The ornamental design for a grid bench with cushions, as shown and described above.

DESCRIPTION

FIG. 1 is a perspective view of the grid bench with cushions;

FIG. 2 is a top plan view thereof;

FIG. 3 is a front elevational view thereof;

FIG. 4 is a left side elevational view thereof; and,

FIG. 5 is a bottom plan view thereof.

A front elevational view is provided of which the back elevational view is identical. A left side elevational view is provided of which the right side elevational view is identical.
